UNITED STATES PATENT OFFICE.

CLARENCE W. WHITE, OF NORTH BENNINGTON, VERMONT.

DESIGN FOR A CHILD'S VEHICLE.

48,957.

Specification for Design.

Patented Apr. 25, 1916.

Application filed December 27, 1915. Serial No. 68,958. Term of patent 14 years.

To all whom it may concern:

Be it known that I, CLARENCE W. WHITE, a citizen of the United States of America, residing in North Bennington, county of Bennington, and State of Vermont, have invented a new, original, and ornamental Design for Children's Vehicles, of which the following is a specification, reference being had to the accompanying drawing, forming part thereof.

Copies of this patent may be obtained for five cents each, by addressing the "Commissioner of Patents, Washington, D. C."

I claim:

The ornamental design for a child's vehicle, as shown.

In testimony whereof I have signed this specification in the presence of two subscribing witnesses.

CLARENCE W. WHITE.

Witnesses:

HARRIET C. WHITE,
LEO J. MATTY.
